UNITED STATES PATENT OFFICE

172,383

TOY INSTRUMENT PANEL FOR CYCLE HANDLE BARS

Leroy Coates, Covington, Ky.

Application May 21, 1953, Serial No. 25,154

Term of patent 14 years

(Cl. D90—1)

To all whom it may concern:

Be it known that I, Leroy Coates, a citizen of the United States of America, residing at Covington, in the county of Kenton and State of Kentucky, have invented a new, original, and ornamental Design for a Toy Instrument Panel For Cycle Handle Bars, of which the following is a specification, reference being had to the accompanying drawings, forming a part thereof, in which:

Fig. 1 is a front elevational view of a toy instrument panel for cycle handle bars, showing my new design, the fragmentary dotted line showing of the handle bars being for illustrative purposes only;

Fig. 2 is a rear elevational view thereof; and

Fig. 3 is an end elevational view thereof.

The dominant features of my design reside in the portions shown in full lines.

I claim:

The ornamental design for a toy instrument panel for cycle handle bars, as shown and described.
